POURING ATTACHMENT FOR CONDENSED MILK

Leon J. Gauvreau, Astoria, N. Y.

Application May 5, 1937, Serial No. 140,825

2 Claims. (Cl. 220—51)

This invention relates to an improved device for pouring evaporated and condensed milk, and other flowing liquids from containers in the form of puncturable cans, and its leading object 5 is to provide a device which can be readily attached to a can, which can be used to form two punctures in the can top, one for the discharge of the contents and the other for the admission of air, and which includes two cooperating levers, 10 each lever carrying one of the piercing prongs with which the puncture on one side of the can top is made, and one lever having a handle which is engageable by the handle of the other lever, so that upon depression of said other lever, both levers will be operated to simultaneously raise two prongs, so that the contents of the can may be poured freely.

Another object of the invention is the provision of a device of this character with a spring 20 arranged to close both levers, so that their prongs will enter and seal the can openings.

With the above and other objects in view the invention consists in certain combinations, constructions, and arrangements of parts, clearly 25 described in the following specification, and fully illustrated in the drawing, in which:—

Fig. 1 is a plan view, showing the improved pouring attachment coupled to the top of a can.

Fig. 2 is a bottom plan view of the attachment 30 removed.

Fig. 3 is a side elevation of the attachment.

Fig. 4 is another side view thereof.

Fig. 5 is a side view of the attachment showing the levers in raised position on the can.

35 Referring to the drawing illustrating the practical embodiment of the invention 5 designates a metal base, adapted to be positioned on the top of a metal container or can. This base is provided on one side with a depending lug 6, which is equipped with a screw threaded bearing 7 through which the clamping screw 8 is threaded, so that the point thereof may engage the side of the can 9. The opposite side of the base 5 is equipped or provided with a pair of pendant lugs 40 10 and 11, which are shown to be spaced apart from each other, see Fig. 4.

The base 5 is formed or provided with a plurality of struck-out lugs 12 and 13, located in opposition to each other, to which the smaller lever 14 is pivoted, by means of the trunnions 15 and 16. This lever includes a flat base portion 17 and a right angular arm or handle 18, which is formed with a curved portion 18a, and this curved handle normally projects upwardly in an 45 approximate vertical position, with the curved

terminal portion disposed in horizontal position.

The lever base 17 is equipped with a piercing prong 19, which is fixed thereto in any suitable manner, and which is located near the outer end thereof, so as to produce a puncture near the 5 rim of the can.

The base 5 is further formed or provided with another pair of lugs 20 and 21, which are located in opposition to each other and which receive the trunnions 22 and 23 of the larger lever 24. 10 This lever includes a base 25 and the handle 26, which is disposed at approximately right angles thereto, and provided with a laterally curved upper end 27. The opposite end of the lever, or of its base, is equipped with a piercing prong 28, 15 suitably attached thereto, and located so as to pierce the can top near the rim thereof. The base 5 is formed with an opening 19' which receives the prong 19, and said base 5 is further provided with another opening 28' to receive 20 the prong 28. These openings are preferably large enough to prevent the fluid which accumulates around the openings formed by the piercing action of the prongs, from building up to interfere with the pouring action. 25

The larger lever is formed with a pendant lip 29, adapted to overlap the rim of the can, and act as a cut-off to prevent dripping of the fluid.

The handle of the larger lever is longer than 30 the handle of the shorter lever, so that when the larger lever is manually pressed the handle of the shorter lever will be engaged, thus simultaneously raising the prongs of both levers, as shown in Fig. 5.

The larger lever is formed with a struck out finger lug 30, which acts as a keeper for the coil 31 of the spring which is provided with one terminal arm 32, which engages the base of the main or larger lever, and for this purpose is 35 formed with a lateral terminal 32a which is inserted in the small hole 32b of said larger lever. The spring is further provided with another arm 33, which projects through a slot 34 formed in the handle of the smaller lever, and which then has sliding engagement with the base of the 40 shorter lever. The two arms of the spring thus act on the bases of the two levers to hold the prongs in the openings so that the can is effectively sealed. 45

The attachment is placed over a container can 50 and the two prongs are forced through the top, and then the base 5 is clamped in place by means of the small clamping screw, thus firmly securing the attachment to the can.

The device is then ready for use, and the con- 55

tents of the container may be poured from either side thereof, but preferably from the side to which the larger lever is attached. As the contents are poured the air is allowed to enter the 5 can.

Having described my invention I claim as new:

1. A pouring attachment for cans, consisting of a base provided with means for gripping the edge of a can, a pair of levers pivotally mounted 10 on the base, each lever having a prong for piercing the top of the can, the levers being mounted so that the prong of one lever will engage one side of the top of the can and the prong of the other lever will engage the opposite side of the 15 can, each of said levers having a rearwardly extending end, one of said ends projecting upward.

ly to form a handle and so constructed and arranged that when said end is moved about said pivotal mounting it will engage and operate the projecting end of the other lever, whereby on depression of said end both of said levers will be 5 raised to open position.

2. The construction set forth in claim 1, including a coil spring carried by one of the levers in substantial alignment with the pivotal mounting thereof, having two arms, one of said arms 16 engaging one of said levers and the other of said arms engaging the other of said levers, whereby each of said levers is spring retained in the closed position.

LEON J. GAUVREAU. 15
